CYLINDRICAL CONVERTER

Herman A. Brassert, Washington, Conn., assignor
to H. A. Brassert & Company, New York, N. Y.,
a corporation of Illinois

Application December 2, 1948, Serial No. 63,158

1 Claim. (Cl. 266—36)

1

This invention relates to the manufacture of steel and it relates particularly to improvements in converters for treating molten iron to convert it into steel.

For many years, converters used in the production of steel have been essentially unchanged despite the fact that these prior converters have been known to have certain inherent defects.

The bottom blow Bessemer converter is still a large pear shaped chamber, as invented by Bessemer, having a pouring nose at one end through which the iron is charged and the steel is discharged by tilting the converter about trunnions which are perpendicular to the axis of the chamber. The blowing air is introduced by means of tuyères in the bottom of the converter so that the air is forced upwardly through the charge thereby converting the carbon in the iron to carbon monoxide with the generation of heat by combustion of silicon and carbon, and the more or less complete removal of both from the charge. Inasmuch as air which is normally used in blowing the charge consists largely of nitrogen, there is a tendency for the nitrogen to be absorbed in the melt. The amount of nitrogen absorbed will depend upon a number of factors, i. e. the deeper the bath, the higher the pressure, the longer the passage of air through the molten metal, the more nitrogen that is picked up by the melt. This is objectionable since a relatively minute nitrogen content renders the Bessemer steel brittle and produces undesirable effects in the final product. Moreover, a great deal of heat is lost by the burning of carbon monoxide to carbon dioxide at the nose of the converter, forming the well known Bessemer flame. This high carbon monoxide content is normal since, the amount of air is introduced into the bottom of the molten bath, where, at the prevailing high temperatures, no CO₂ can exist in the presence of carbon and therefore combustion is incomplete and only to carbon monoxide. Due to the fact that the heat available in the converter is rather limited, the amount of scrap that can be melted in the converter is also limited.

Another less widely used type of converter is the side blow type. In this type of converter, the blowing air is introduced through tuyères near the surface of the charge. There is much lower nitrogen absorption, but this type of converter cannot handle a large charge, and moreover, because the air is introduced near the surface, a relatively greater blowing time is required to remove the impurities than with the conventional bottom blow type.

2

It has been suggested that a conventional bottom blow type of converter can be used in such a way that both a bottom and a side blow is obtained by tilting the converter so that some of the bottom tuyères are disposed above the surface of the charge in the converter. This expedient is not very practical, however, for the reason that the charge must be kept very small in order that a reasonable tilting movement of the converter will expose some of the bottom tuyères above the level of the charge. Under these circumstances, only a small charge can be treated in the converter as compared with the charge when the converter is used in the normal way.

It is clear that the prior types of pear shaped converters have left considerable to be desired particularly from the standpoint of producing a relatively nitrogen-free steel at a high production capacity.

An object of the present invention is to provide a converter for producing steel in which a very close control of temperature, and treating time with resultant low nitrogen absorption may be obtained while handling a relatively large volume of the iron for conversion into steel.

Another object of the invention is to provide a converter in which much larger quantities of scrap can be used in the production of the steel than with the prior types of converters and which, at the same time, permits the desirable close control of the treating conditions.

A still further object of the invention is to provide a converter having the tuyères arranged therein in such a way that the blowing of the charge can be stopped at any time to permit samples to be taken and additions to be made without in any way endangering the blowing operation by clogging of the tuyères.

Another object of the invention is to provide water cooled elements in the converter lining to protect it against impinging slag and flames. Another object is to mount the tuyères in a water cooled frame so that they may be easily replaced and/or changed.

Other objects of the invention will become apparent from the following description of a typical form of converter embodying the present invention.

In accordance with the present invention, I have provided a converter which is in the form of a cylinder mounted for rotation about its axis, the latter being disposed in a substantially horizontal plane so that the cylindrical converter can be rocked back and forth to permit the intro-

duction of a charge into the converter and to discharge the steel therefrom.

A particular feature of the converter is the provision of tuyères extending lengthwise of the converter, these tuyères being so positioned that they may be rocked into positions above or below the level of the charge in the converter or so that they are disposed above and below the surface of the charge in the converter. Preferably, such blowing tuyères are mounted along only one side of the converter so that when the converter is rocked into the charging and discharging positions, the tuyères will be disposed entirely above the level of the charge thereby permitting samples to be withdrawn and also preventing the metal from clogging the tuyères if the blowing operation is discontinued during sample taking.

Another feature of the invention is the provision of a novel cooling arrangement for the tuyères so as to prevent them from being destroyed or damaged from the intense heat within the converter.

A converter of the type described generally above has numerous advantages, the principal one being the close control of the blowing operation. Thus, during the initial blowing operation, it is possible to dispose the tuyères so that they are completely or partially below the surface of the charge in the converter. When the tuyères are disposed completely below the surface, the blowing operation is similar to that with the conventional Bessemer converter. If part of the tuyères are disposed above the level and part below, the combined effects of side blowing and bottom blowing are obtained. Under these conditions, there is a rapid conversion of the carbon to carbon monoxide in the charge and a very rapid burning of the carbon monoxide to carbon dioxide at the surface of the charge which results in the generation of greater heat, thereby permitting greater amounts of scrap to be introduced into and melted in the charge. The inclusion of large quantities of scrap greatly facilitates the production of steel and increases the rate of production. Moreover, by blowing a part of the air above the surface, a much smaller amount of nitrogen is absorbed in the steel, for only a part of the blast is in intimate contact with the steel. In addition to the foregoing, the arrangement is such that the amount of oxygen supplied to the charge may be closely controlled, and, if desired, oxygen may be added directly to the air thereby increasing the oxygen content of the blast to generate more heat and this enriched blast will also further reduce the tendency of the metal to absorb nitrogen.

For a better understanding of the present invention, reference may be had to the accompanying drawings, in which:

Fig. 1 is a view in side elevation and partly in longitudinal section of a typical form of converter embodying the present invention;

Fig. 2 is a view in cross section taken on line 2-2 of Fig. 1 with the converter shown in the blowing position;

Fig. 3 is a view in elevation of one of the tuyère assemblies of the converter;

Fig. 4 is a view in section taken on line 4-4 of Fig. 3;

Fig. 5 is a view in section taken on line 5-5 70 of Fig. 4; and

Fig. 6 is a view in section taken on line 6-6 of Fig. 3.

Figs. 1 and 2 of the drawings illustrate a typical form of converter embodying the present in-

vention which may be made in any desired size suitable for the purpose. Thus, such converters may range in size from 25 tons capacity or smaller to 100 or more tons if desired. The converter includes a cylindrical metal shell 10 which is provided with curved end portions 11 and 12 also formed of steel or other similar metal, the entire shell being provided with a heat resistant lining 13 of brick or other suitable material. At about the mid-portion of the shell is provided the charging and discharging nose portion 14 of the converter which, as shown in Fig. 2 is tapered. The nose portion 14 may be formed of a conical metal shell 15 provided with a refractory lining 16, and, if desired, may be provided with a removable lip portion 17 which is joined to the remainder of the nose portion 14 by means of suitable interconnected flanges 18.

Near the opposite ends of the shell 10 are provided the tracks 19 and 20 which are generally sector or arcuate shape. Each of the tracks, for example track 20, may consist of an arcuate inner band member 21, welded or otherwise secured to the shell 10, and an outer concentric band member 22 which is retained in spaced relation to the band 21 by means of a series of spacer plates 23 and 24 which form a rigid and strong supporting structure. The tracks 19 and 20 are mounted on antifriction supports. Each of these supports includes a plurality of rollers 25 which are rotatably mounted on shafts 26 extending between a pair of arcuate side plates 27 and 28 which form, in effect, races for the rollers. The rollers 25 are, in turn, supported upon the heavy base member 29 which, as shown in Figs. 1 and 2, have arcuate tracks 30 upon which the rollers 25 roll.

The converter may be rocked around its axis by means of an arcuate rack 31 located at about the mid-portion of the shell 10, this rack engaging a gear 32 which is driven by means of a speed reducing mechanism 33 and an electric motor 34 or other equivalent device. The motor is preferably of the reversing type so that the converter can be rocked back and forth.

As best shown in Fig. 2, the converter is provided with a bustle pipe 35 extending along and connected to one side of the shell 10, this pipe communicating with a plurality of tuyères 36 which extend through the side of the converter, and in the position shown in Fig. 2, are directed upwardly toward the surface of the charge C in the converter. The bustle pipe 35 is connected at its opposite ends to tubular members 37 and 38 to which air or air and oxygen is supplied through suitable rotary couplings (not shown). The members 37 and 38 are connected to the bustle pipe 35 by means of the radially extending pipes 39. If desired, several such bustle pipes and sets of tuyères may be arranged around the converter.

As evident from Fig. 2, the converter can be rotated into a position in which the nose portion 14 is disposed to approximately a 30° angle from the horizontal plane in order to receive a charge. Also, as evident from Fig. 2, the converter can be rotated to bring the nose 14 into a downwardly inclined position to discharge the molten steel from the converter.

In the blowing position, which is shown in Fig. 2 the converter is rocked so that the nose portion 14 is disposed counterclockwise from the vertical in order to dispose the tuyères either below or above the surface of the charge or partly below and partly above as required. In this way, a controlled blowing can readily be obtained to make

the best use of the heat available in the carbon and to reduce nitrogen absorption to a minimum.

Inasmuch as the tuyères are subjected to intense heat, provision is made for cooling these tuyères as described hereinafter.

A suitable tuyère arrangement and cooling system therefore is shown in Figs. 3 to 6. As illustrated in Fig. 3 each of the tuyère assemblies having the several tuyères 36 may include a generally hollow box-like member 40 having an arched frame-like front plate 41 which is adapted to overlie the portions of the shell 10 adjacent an opening 42 through the wall of the converter. As many such openings may be provided as may be required to accommodate the several sets of tuyères 36. The shell 10 is provided with upper pairs of lugs 43—43 and lower pairs of lugs 44—44 which are received in notches 45—45 and 46—46, respectively, in the front plate 41. Cross pins 47 extend through these lugs to retain the frame 40 in position.

The openings 42 in the walls of the converter converge inwardly on generally radial lines and receive snugly the hollow housing 41a which extends rearwardly from the front plate 41. As best shown in Figs. 5 and 6, the housing 41a is generally rectangular in cross section. Also, as shown in Fig. 4, it has an upper hollow wall portion 41b and lower hollow wall portion 41c which are substantially coextensive in length with the thickness of the wall of the converter, and an open inner end portion 49.

The hollow center portion of the member 40 has a filler 50 of tuyère brick through which extend the parallel tuyères 36 referred to above. These passages are substantially perpendicular to the inner face 49 of the box and communicate with the bustle pipe 35 which is disposed on the outside of the shell.

The tuyères are cooled by introducing water into the tuyère box 40 around the brick filler 50. As shown in Figs. 3 and 4, water may be introduced through the opening 52 in the lower left-hand corner of the frame 41 so that it flows through the hollow wall portion 41c of the box upwardly through the side passages 54 and 56 in the hollow side walls 57 and 58, then into the hollow top portion 41b and along the hollow side walls 57 and 58 to the discharge outlet 59 in the upper right hand corner of the frame 41. Each of the hollow side walls 57 and 58 may be provided with a downwardly extending partition 60 so that the water follows the path shown generally in dotted lines in Fig. 4, thereby assuring circulation of water around the entire outside of the tuyère brick filler in the box. In order to avoid trapping of steam or air in front of the partition 60, it may be provided with a vent opening 61 through which the air or steam can escape to the water outlet 59.

The above-described tuyère construction has the advantage that cooling water may be circulated continuously around the tuyères so that destruction of the tuyères by overheating is to a large extent overcome. The water may be introduced into the openings 52 through a cooling water line 62 shown in Fig. 2 and discharged through a cooling water discharge line 63 extending lengthwise of the bustle pipe 35.

The tuyères can be attached to and detached from the converter to permit their repair or replacement. To facilitate removal of the tuyères, the front frame member 41 may be provided with the ears 66 and 67 on its opposite sides, as shown in Fig. 3, in which are mounted set screws 68 and

69 which may be turned up against the shell of the converter to force the tuyère box 40 out of the opening 42.

Water-cooled elements 40a, similar in construction to the above-described tuyère boxes 40, but imperforate, are inserted in the converter lining opposite the tuyères 36, as shown in Fig. 2, in order to protect the lining against impinging slag and flame.

10 The above-described converter permits a more precise control of the blowing conditions within the converter, for as indicated above, the action of the blast on the charge may be changed from a bottom blow to a top or side blow operation, and, more particularly, a very closely controlled combined top and bottom blow can be produced by suitably positioning the tuyères with the result that the amount of nitrogen absorbed in the charge can be held to the desired minimum while the amount of available heat for melting scrap and other purposes may be very substantially increased. Moreover, by arranging the converter horizontally, a very large charge in proportion to the size of the converter can be handled quickly and efficiently.

25 The apparatus may be provided with suitable controls whereby oxygen can be added to the blowing air and may be adjusted so that a predetermined proportion of added oxygen can be 30 maintained in the blowing air once the control mechanism has been set for optimum operating conditions. In this way, it is possible to obtain a much closer control of the blowing operation than with the prior types of blowing devices in 35 which a high degree of skill by the operator is required. Moreover, the arrangement of the tuyères in the side of a rockable converter of this type permits freedom of sampling and freedom of discharge of the blown charge with the blast 40 cut off without danger of clogging the tuyères by freezing of the molten metal therein. Moreover, damage to the tuyères by high temperatures is largely overcome by the water cooling system provided in this converter.

45 It will be understood that the converter is susceptible to considerable modification, and that, if desired, one or more rows of tuyères may be provided in the converter. Accordingly, the form 50 of the converter disclosed herein should be considered as illustrative of the invention and not as limiting the scope of the following claim.

I claim:

A converter for producing steel comprising a cylindrical chamber for receiving a charge of iron, 55 a refractory lining in said chamber, means for supporting said chamber for rocking movement about its axis with the latter in a horizontal plane, a charging nose portion at about the mid-portion of said chamber, a wind box extending lengthwise of and fixed to the outside of said chamber, 60 a row of tuyères connected to said wind box for directing air into the chamber, said tuyères comprising a frame member having hollow walls defining a space extending from the front to the back of the frame member, a tuyère brick filling in said space having tuyère openings therethrough, and means for circulating cooling water through said hollow walls to cool said filling; a water cooled member opposite to said tuyères and adjacent to said nose portion to protect said lining against impinging slag and flame, and means for rocking said chamber between a position in which the tuyères are disposed entirely below the surface of the charge and the nose portion is directed upwardly, and a position in which the nose

is directed downwardly and the tuyères are entirely above the surface of the charge.
